UNITED STATES PATENT OFFICE.

SILAS P. TOMKINS, OF TILLY FOSTER, NEW YORK.

DESIGN FOR A SAFETY-PIN.

SPECIFICATION forming part of Design No. 30,131, dated February 7, 1899.

Application filed January 10, 1899. Serial No. 701,762. Term of patent 7 years.

To all whom it may concern:

Be it known that I, SILAS P. TOMKINS, of Tilly Foster, in the county of Putnam and State of New York, have invented a new and 5 original Design for a Safety-Pin, of which the following is a specification, reference being had to the accompanying drawing, forming a part thereof, in which is represented a perspective view of a safety-pin embodying the 10 features of my design.

The design consists in a coil A, from which a pin B extends into a limb of a U-shaped keeper C, a rod D, that extends from the other limb of the keeper to a twist engagement D' 15 with a second rod E, that is a continuation of

the said coil, and a loop hook F, that extends partially parallel with the rod D in direction of the keeper.

The leading feature of the design consists of a safety-pin and a hook adjacent to a longitudinal member of the pin practically in parallelism therewith and extending in direction of the keeper of the pin. 20

I claim—

The design for a safety-pin, herein shown 25 and described.

SILAS P. TOMKINS.
